D. M. BALLOU

CLIP FOR PENCILS

Filed Feb. 14, 1925

Patented Jan. 5, 1926.

1,568,950

UNITED STATES PATENT OFFICE.

DAVID M. BALLOU, OF PROVIDENCE, RHODE ISLAND, ASSIGNOR TO REX MFG. CO., OF PROVIDENCE, RHODE ISLAND.

CLIP FOR PENCILS.

Application filed February 14, 1925. Serial No. 9,137.

To all whom it may concern:

Be it known that I, DAVID M. BALLOU, a citizen of the United States, residing at Providence, in the county of Providence and State of Rhode Island, have invented new and useful Improvements in Clips for Pencils, of which the following is a specification.

This invention relates to certain new and useful improvements in clips for pencils, and the primary object of the invention is to provide effective and simplified means for enabling the clip to be easily and quickly applied to a pencil or to a pen.

The invention has still further and other objects which will be later set forth and manifested in the course of the following description.

In the drawings:—

Figure 1 is a side elevation of a pencil, partly broken away and in section to illustrate the invention.

Figure 2 is a section on line 2—2 of Fig. 1.

Figure 3 is a detail view of the clip, and

Figure 4 is a like view of the fastening collar prior to inturning of the edges thereof.

In proceeding in accordance with the present invention an outer casing 1 is employed into the outer end of which a metal plug 2 having a head 2" is threaded. The plug 2 rotatably supports the operating tube 3 by means of a bead 3" on the tube, the tube being for the purpose of expelling and retracting the lead, by means associated with the tube, not illustrated.

The upper end of the plug is formed with an outwardly projecting circular collar 4 which latter is projected through the aperture of a ring-like head 5 formed on the inner end of the clip 6, the head being disposed at substantially right angles to the arm portion of the clip, which arm portion lies along the casing.

A ferrule 7 has its edge 8 inturned and clamped between the plug 2 and the outer casing 1, while the upper edge 10 of the ferrule is cut-out at 9 to receive the outer end of the clip arm and is bent over onto the head 5 to hold the latter firmly on and against the outer end of the plug 2.

The sleeve 11 which carries the eraser or rubber plug has an inturned bottom 12 and has a disk 13 seated on the edge of an ex-

tension 14 of the sleeve, the same being rotatable relative to the collar 4, the extension being formed hollow to fit over and be fixed to the tube 3. The free edge 15 of the tube 3 is spun outwardly over the disk 13 thereby to hold the sleeve 11 in position.

From the foregoing it will be seen that the sleeve 11, conceals the inturned edge 10, of the collar, and also the head 5, so as to present a finished appearance of the parts, and in addition the casing 1, can be unscrewed from the plug 2, if desired without disturbing the remaining described parts.

Having thus described my invention what I claim as new and desire to secure by Letters Patent is:—

1. In a writing instrument, an outer casing having a plug threaded in its outer end and a tube in the plug, a clip having a substantially ring-like head, a collar on the plug received in the opening of said head, a ferrule having inturned end edges one of which is clamped between the casing end and plug and the other of which is engaged over said head to hold same onto the plug and a sleeve seated on the outer edge of the ferrule and having a part engaged with the tube, the adjacent edge of the tube being extended at an angle and engaged with said part of the tube.

2. In a writing instrument, an outer casing having a plug threaded in its outer end and a tube in the plug, a clip having a substantially ring-like head, a collar on the plug received in the opening of said head, a ferrule having inturned end edges one of which is clamped between the casing end and plug and the other of which is engaged over said head to hold same onto the plug, and a member on the outer end of the tube overlying the outer edge of the ferrule.

3. In a writing instrument, an outer casing having a plug threaded therein, a clip having a head seated on the plug, and a ferrule surrounding the plug and having inturned edges one of which latter is clamped between the plug and casing and the other of which engages over the head to hold the latter onto the plug.

4. In a writing instrument, an outer casing, a member engaged with the casing, a clip having a head seated on said member, and holding means for the clip having a part engaged over and with the head to hold same onto the member and also having

a part engaged with the member thereby to secure the holding means in position.

5. In a writing instrument, a casing, a plug having a reduced part forming a shoulder carried by the casing, a clip having a head engaged over the reduced part and against the shoulder, and a member surrounding the head and clip and having an inturned part engaged with the head to hold 10 same against the shoulder and having a part formed with an inturned portion engaged with the plug to rigidly secure the head thereto.

6. In a writing instrument, a casing, a plug engaged with an end of the casing, a clip having a head engaged with the plug, and means encircling the plug and head and having inturned parts one of which engages over the head to rigidly clamp same to the plug 15 and the other of which is engaged with the plug so as to be fixedly connected thereto.

7. In a writing instrument, a casing, a member removably connected to the casing, a clip having a head engaged with the member, a ferrule engaged about the head and member and having inturned portions one 20 of which engages the head and the other the member to rigidly connect the head to the member.

8. In a writing instrument, a casing, a plug having a reduced part forming a shoulder carried by the casing, a clip having a head engaged with the shoulder, and a 25

member engaged about the head and plug and having inturned parts one of which 35 clamps the head against the shoulder and the other of which engages the plug so as to rigidly connect the head to the plug.

9. A writing instrument having a casing, a threaded bearing guide plug screwed into 40 one end of said casing, said plug having a shoulder and a collar portion extending above said shoulder, a spring clip having a resilient arm lying along said casing and having a laterally extending end with an 45 opening therein embracing said collar, and means being provided for securing said clip end to said shoulder.

10. A writing instrument having a casing, a threaded bearing guide plug screwed 50 into one end of said casing, a spring clip having a resilient arm lying along said casing and having a laterally extending end immovably secured to the plug to prevent a 55 relative rotation of said clip and plug.

11. A writing instrument having a casing, a threaded bearing guide plug screwed into one end of said casing, a spring clip having a resilient arm lying along said casing and having a laterally extending end with an 60 opening therein receiving a portion of said plug, and means for securing said clip end to said plug.

In testimony whereof I have signed my name to this specification.

DAVID M. BALLOU.
